CLAIM

The ornamental design for a cap for a writing instrument, as shown and described.

DESCRIPTION

FIG. 1 is a front elevational view of a cap for a writing instrument according to the present invention;

FIG. 2 is a rear elevational view thereof;

FIG. 3 is a right elevational view thereof, the left side being a mirror image thereof;

FIG. 4 is a top plan view thereof;

FIG. 5 is a bottom plan view thereof;

FIG. 6 is a front elevational view of a second embodiment of our new design;

FIG. 7 is a rear elevational view thereof;

FIG. 8 is a right elevational view thereof, the left side being a mirror image thereof;

FIG. 9 is a top plan view thereof; and,

FIG. 10 is a bottom plan view thereof.
